MEMORANDUM PAD WITH ROLLED MEMORANDUM PAPER

Walter F. Lucas, Bellerose, N. Y.

Application February 10, 1953, Serial No. 336,095

1 Claim. (Cl. 281—6)

The memorandum pad which is described and claimed herein consists of the following component parts: A writing pad, a container at one end of the writing pad which is adapted to accommodate a roll of writing paper, a keeper in said container which engages the roll of writing paper and maintains it in predetermined position while allowing it to rotate on its longitudinal axis in order to feed paper to the writing pad, and an opening in said container through which the paper may be fed from its roll to the writing pad, a slit being formed in the writing pad at its opposite end from the end occupied by the container and being adapted to receive the paper which is fed from the roll, and a cutting edge on said writing pad adjacent said slit, against which the paper may be severed after use.

This device is intended to be a simple, inexpensive memorandum pad of the character described. The container may readily be opened to insert a roll of writing paper and it may equally as readily be closed. The roll may very easily be inserted into the keeper so as to properly position it and the paper from said roll may very easily be fed through the opening in the container. It is brought across the writing pad and through the slit in said writing pad. When the writing pad is placed on a desk or table or any other suitable horizontal support, the paper which projects through said slit is held between the writing pad and the desk or table top so that it will not shift when a memorandum is written thereon. The cutting edge to which reference has above been made may simply be the front edge of the writing pad, either with or without a blade or cutter attachment. The paper may be drawn from the roll by simply pulling upon that portion of the paper which projects through the slit in the writing pad. When it is drawn out to the point where it is desired to sever the paper, the pad is simply placed upon the desk or table and held there with one hand while the paper is severed against the leading edge of the writing pad with the other hand.

It is accordingly the principal object of this invention to provide a memorandum pad of the character above described. The preferred form of this invention is made of extremely inexpensive material, such as cardboard or plastics or the like. Although the invention will be illustrated in terms of cardboard as the material of which it is made, it will of course be understood that it may be made of other materials such as the plastics above mentioned and also stamped or die-cast metal, leather and even wood.

A preferred form of this invention is shown in the accompanying drawing in which:

Fig. 1 is a top view of a memorandum pad made in accordance with this invention.

Fig. 2 is a longitudinal section on the line 2—2 of Fig. 1.

Fig. 3 is a top view with the paper roll container in open position to reveal the paper roll itself and the keeper for said roll.

Fig. 4 is a plan view of a blank from which the bottom

2

layer of the writing pad and also a part of the container and the paper roll keeper are made.

Fig. 5 is a plan view of the blank from which the top layer of the writing pad and also a part of the paper roll container are made.

Fig. 6 is a perspective view of a memorandum pad made in accordance with this invention, showing the provision of a tubular holder for a pencil.

Referring now to the drawing it will be seen that the memorandum pad 10 herein claimed comprises a writing pad 12, a container 14 for a roll of paper 16, and a keeper 18 in said container for said roll of paper. The strip of paper 20 which is fed from said roll projects through a hole of elongated shape 22, extends across the top of writing pad 12, then dips down through slit 24 in said pad and finally passes between said writing pad and table or desk top 26.

It has been stated that this memorandum pad may be made of any suitable material but in the illustrated form of the invention it is made of cardboard and, more particularly, of two cardboard blanks 28 and 30 respectively. Cardboard blank 28 forms the bottom layer of the writing pad and also a part of the container and the keeper. Blank 30 forms the upper layer of the writing pad and the rest or remaining part or parts of the container.

It will be noted in Fig. 4 that blank 28 is a substantially rectangular sheet of cardboard with a transverse slit 32 formed therein adjacent and parallel to its leading edge 34. At the opposite end of blank 28, a rectangular opening 36 is formed and one of the edges of said rectangular opening is aligned with a pair of transverse folding lines 38 and 40 respectively. Paralleling said edge of opening 36 and also folding lines 38 and 40 are three spaced folding lines 42, 44 and 46 respectively. Between folding lines 44 and 46 a shallow U-shaped slit 48 is formed.

Turning now to Fig. 5 it will be seen that blank 30 also has a slit 50 formed therein, corresponding in size, shape and location to slit 32. At the opposite end of blank 30 is a flap 52. In front of said flap is a pair of spaced, parallel transverse folding lines 54 and 56 respectively. A pair of side flaps 58 and 60 are formed on the sides of blank 30 between folding lines 54 and 56 and it will be noted that folding lines 62 and 64 are formed along the lines of juncture between side flaps 58 and 60 on the one hand and the main body of blank 30 on the other hand. There are also transverse folding lines 66 and 68 across flaps 58 and 60. A slit 70 is formed across blank 30 in parallel relation to folding lines 54 and 56 and the ends of said slit 70 are joined to the side edges of blank 30 by means of folding lines 72 and 74.

In making the memorandum pad herein claimed, blank 30 is superimposed upon blank 28 so that its side edges coincide with the side edges of blank 28 and its leading edge 76 coincides with the leading edge 34 of blank 28. Similarly, slits 50 and 32 are brought into registration with each other. The two blanks are glued or cemented together in the area bounded by the side edges of the two blanks, the leading edges 34 and 76 of the two blanks and folding lines 72 and 74 of blank 30. Blank 28 continues backwardly on the same plane as that portion which is glued or cemented to blank 30 until folding line 46 is reached. The portion of blank 28 between folding lines 46 and 44 is then bent upwardly at right angles to said plane. The portion between folding lines 44 and 42 is then bent downwardly into parallel relation to the upwardly extending portion between folding lines 46 and 44. The portion between folding line 42 and folding lines 38 and 40 then rests upon the main body of the blank in parallel relation thereto, and the portion between said folding lines 38 and 40 on the one hand

and back end 78 on the other hand is then bent backwardly to occupy a diagonal position between said folding lines 38 and 40 and folding line 44.

The portion of blank 30 which occupies the space between folding lines 72 and 74 and folding line 56 is, 5 bent upwardly into parallel relation to the portions between folding lines 46 and 44 and 44 and 42 of blank 28. The portion between folding lines 56 and 54 is then bent backwardly into horizontal position in parallel relation to the plane above mentioned. The portion between folding line 54 and the back edge 80 of blank 30 is then folded downwardly and tab 52 is inserted through slit 48 and between the two portions which occupy the spaces between folding lines 46 and 44 and between 44 and 42. 10 Side flaps 58 and 60 are then bent downwardly and they are folded inwardly along folding lines 66 and 68. The end portions beyond said folding lines are tucked between the main body of blank 28 and that portion of said blank which lies between folding line 42 and folding lines 38 and 40. The memorandum pad herein claimed is now 15 completely assembled.

Relating the sections of the two blanks which have last been described to the finished memorandum pad herein claimed, it will be seen that the two portions of the two blanks which are glued or cemented to each other constitute the writing pad 12 and the two leading edges 34 and 76 combine to form the cutting edge of said memorandum pad. The portion of blank 30 between folding line 56 and folding lines 72 and 74 constitutes the front wall 82 of container 14. The portion between folding lines 56 and 54 constitutes the top wall 84 of said container. Flaps 58 and 60 between folding lines 62 and 64 on the one hand and 66 and 68 on the other hand constitute the end walls 86 and 88 of the container. There is a double back wall 90 and 92 formed of the portions between folding lines 46 and 44 and 44 and 42 of blank 28. The portion between edge 80 and folding line 54 of blank 30 constitutes the back cover or flap member 94. The portion between folding line 42 and folding lines 38 and 40 of blank 28 becomes floor 96 of container 14. The portion between folding lines 38 and 40 and back edge 78 becomes the keeper 18 of paper roll 16.

When the paper roll is mounted in container 14, it occupies opening 36 in keeper 18. The sides of said opening 36 prevent endwise movement of the roll of paper and said roll is always maintained thereby in alignment with slits 70 and 32 and 50. Paper 20 is fed from roll 16 through slit 70 and it extends across the top of the writing pad 12 as the drawing clearly shows. It then dips down through slit 24 which slits 32 and 50 combine to form and it projects under the forward end of said writing pad. When the writing pad is held down upon the table with one hand, the paper may be severed along edges 34, 76 with the other hand.

The foregoing is illustrative of a preferred form of this invention and it will clearly be understood that this preferred form may be modified and other preferred forms may be had within the broad spirit of the invention and the broad scope of the claims. For example, the precise shape of container 14 as shown in the drawing is not critical. The drawing shows it to be a rectangular box-like container but it will be understood that the invention is not limited to a container of this shape, bearing in mind, that the article which it is to contain is a cylind-

rical roll of paper. Other variations are clearly possible and available within the scope of the invention.

Illustrative of a variation which does not in any way involve a variation in the principle of this invention is shown in Fig. 6. Memorandum pad 100 shown in Fig. 6 is made precisely like memorandum pad 10 above described except that it is provided with a tubular holder 102 for a pencil 104. This tubular holder may be made and attached to the memorandum pad proper in any suitable manner but a preferred construction and a preferred method of affixation are shown in Fig. 6. It will be noted that tubular holder 102 is simply a curled or rolled end portion of sheet 106. This sheet 106 may be made of cardboard or plastics or textile fabric, whether laminated for stiffness or not. A portion of this sheet is provided with a coating 108 of a suitable cement or adhesive and it will be noted that this coated portion projects inwardly into container 14 through slit 22. The coated surface abuts the inside of the front wall of said container and the sheet is held in position against said front wall by adhesion. The opposite end of said sheet projects outwardly from said container through slit 22 and it is curled over to form the tubular holder 102. It may be glued or cemented to retain its tubular shape.

I claim:

A memorandum pad of the character described, comprising a substantially rectangular container adapted to accommodate a roll of paper, said container having flat, rectangular top, bottom, back, front and side walls, an opening formed in the front wall of said container through which the paper may be drawn from said roll, a substantially rectangular writing pad supporting said container at one end and receiving and supporting the paper which is drawn from said roll, an opening formed in said writing pad at the opposite end thereof through which the paper may be drawn to a position below said writing pad, and a cutting edge on said opposite end of the writing pad against which the paper which is drawn below said writing pad may be cut and severed a keeper being provided in the container to engage the roll of paper and to prevent axial movement thereof while allowing rotational movement when the paper is drawn from the roll, said keeper comprising a frame having an opening formed therein which accommodates said roll of paper, said opening being rectangular in shape and said frame having four inner edges fronting on and defining said rectangular opening, said edges being adapted to engage the front, back and ends of the roll of paper to maintain its position in said container in alignment with the opening in said container through which the paper is drawn and in alignment with the opening in the writing pad through which the paper is brought to a position below said writing pad.
